GRINDER SHIELD

Filed Sept. 26, 1928

UNITED STATES PATENT OFFICE

ANDREW C. FREY, OF JACKSON, MICHIGAN

GRINDER SHIELD

Application filed September 26, 1928. Serial No. 308,528.

This invention relates to an improved shield for use in conjunction with emery grinders and the like and seeks, among other objects, to provide a device which will effectually protect the operator from injury such as might be caused by flying pieces of steel and emery dust when the grinder is in operation.

Another object of the invention is to provide a grinder shield which will serve the purpose intended and yet provide a clear view of the work being introduced to the grinder.

A further object of the invention is to provide a grinder shield which may be adjusted to different angular positions with respect to the emery wheel of the grinder.

Other objects of the invention not specifically mentioned in the foregoing will appear during the course of the following description.

In the drawings:

Figure 1 is a side elevation showing the device in position on a grinder.

Figure 2 is a top plan view of the device.

Figure 3 is a sectional view of the device on the line 3—3 of Figure 2, looking in the direction indicated by the arrows.

Referring now to the accompanying drawings, the numeral 1 indicates a grinder having an emery wheel 2 about which is a housing 3 provided with an opening 4 for exposing the wheel at the front of the housing so that work may be readily introduced to said wheel for the grinding operation.

In carrying the invention into effect, I employ a base 5 having a concave bottom face to conform to the curvature of the peripheral wall of the housing, and extending through each end of the base is a bolt 6 for securing said base in firm position on the housing.

Formed medially on the base 5 and extending upwardly and forwardly is an arm 7 terminating in a yoke 8, and associated with said arm is a substantially rectangular body frame 9. Formed on the upper side bar of the frame is a shank 10 provided with an eye 11 fitting movably into the yoke 8 and extending through the side portions of the yoke 50 and eye is a bolt 12 swingingly connecting

the frame with the arm of the base 5. Formed in the inner edge of the frame 9 is a rabbet 13 and lying in said rabbet is a glass pane 14. Overlying the upper and lower margins of said pane are gaskets 15 and 16.

Mounted on the body frame and overlying the gasket 16 is a clamping frame 17 substantially rectangular to conform to the body frame 9 and having end bars 18 and upper and lower side bars 19. Extending through said clamping frame at each corner thereof is a screw 20 for securing said clamping frame to said body frame. Formed on the end bars of the frame are outwardly tilted guard flanges 21, and formed on the upper side bar is an outwardly tilted connecting guard flange 22, said flanges providing an enlarged shielding surface and reinforcement for three sides of the clamping frame. These flanges will deflect particles of steel and emery dust and keep them from striking the face of the operator and will also tend to prevent such particles from being deposited on the glass pane to obscure the view therethrough.

Formed medially in the upper side bar of the clamping frame is a notch 23 and extending freely through said notch is an adjusting bolt 24 screwed through the body frame to engage the housing 5. Carried on said bolt is a locking nut 25. In use, the device may be adjusted to various angular positions relative to the wheel by adjusting the bolt 24, which may be secured in adjusted position by tightening the locking nut 25.

What is claimed is:

1. A grinder shield including a body frame, a transparent element carried thereby, and a clamping frame securing said element in position and provided with shielding means reinforcing the frame and upstanding about said element for shielding the same.

2. A grinder shield including a body frame, a transparent element carried thereby, and a clamping frame securing said element in position and provided with guard flanges reinforcing the frame and upstanding about said element for shielding the same.

3. A grinder shield including a body frame, a transparent element carried thereby, and

a clamping frame securing said element in position and provided with guard flanges reinforcing the frame and upstanding about said element for shielding the same, said flanges being tilted outwardly for deflecting flying particles away from said elements.

5 In testimony whereof I affix my signature.
ANDREW C. FREY. [L. S.]
